UNITED STATES PATENT OFFICE.

ALFRED NEWTON CHANDLER, OF LEBANON, TENNESSEE.

BACK-BAND HOOK.

SPECIFICATION forming part of Letters Patent No. 369,229, dated August 30, 1887.

Application filed June 25, 1887. Serial No. 242,511. (No model.)

To all whom it may concern:

Be it known that I, ALFRED NEWTON CHANDLER, a citizen of the United States, residing at Lebanon, in the county of Wilson 5 and State of Tennessee, have invented certain new and useful Improvements in Back-Band Hooks; and I do declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Figure 1 of the drawings is a representation of this invention and is a front view. Fig. 2 is a vertical section. Fig. 3 is a detail and a perspective view. Fig. 4 is also a detail and is a vertical section.

20 The invention relates to improvements in back-band hooks; and it consists in the construction and novel combination of parts, as hereinafter set forth.

Referring to the drawings by letter, A designates the back-band (on one side) having the transverse series of openings or eyelets 25 *a*, and B is the corresponding draft-chain.

C is the band-hook, having a frame portion, D, provided with the upper and lower 30 bars, *c* *d*, respectively, and with the middle bar, E, provided with the inwardly and downwardly standing series of teeth or hooks, *e*, which are adapted to engage in the openings or eyelets *a*. The neck F of the hook is composed of the two curved arms *f* *f*, forming 35 between them the shoulder *g*, beyond which the arms coalesce into a shank, G, provided on its outer surface with the groove H, and on its end with the transverse rib *h*, having 40 its inclined side outward.

I is a bar the lower part of which fits into the groove H, which aids in retaining it in position. The upper end of said bar is formed with a hook, *i*, which engages over the rounded 45 central portion, J, of the lower bar, *d*, of the part D in such manner that it can be disengaged therefrom, and the lower end of the bar has standing inward from it a spring-arm, K, provided with a groove, *k*, that engages the 50 rib *h* on the shank G.

L is a shoulder on the inner side of the bar, which shoulder engages against the shoulder *g* when the parts are in position.

M is an arm standing upward from the in-

ner side of the shank G, and forming a seat 55 for the draft-chain; and N is an arm standing downward from the inner surface of the bar I. The ends of the arms M and N adjoin, and are beveled downwardly and inwardly at their meeting ends. 60

In practice the hooks *e* engage in the holes or eyelets *a*, and a link of the draft-chain rests in the space between the shank and the arms M and N, the adjoining links abutting against the edges of the shank when in place. 65

Operation: The hooks *e* are first engaged in the eyelets, the chain is then placed in the seat formed by the arm M, and the bar I is then hooked to the bar *d* and sprung in place, the arm N preventing the displacement of the 70 chain.

Having described my invention, I claim—

1. The herein-described back-band hook, consisting of an upper flat portion provided with a series of transverse hooks to engage a 75 corresponding series of openings or eyelets in the back-band, a shank having an arm forming between itself and the shank a seat for a link of the corresponding draft-chain, and a detachably-connected bar having an arm aligned 80 with and above the arm on said shank, and serving to prevent the escape of the link, substantially as specified.

2. A back-band hook consisting of the frame portion D, having the upper and lower bars, 85 *c* *d*, respectively, and the middle bar, E, provided with the hooks or teeth *e*, the neck F, provided with the shoulder *g*, arm M, groove H, and rib *h*, and the bar I, provided with the shoulder L, arm N, spring-arm K, and hook 90 *i*, engaging over the round central part, J, of the bar *d*, substantially as specified.

3. The combination, with the draft-chain and back-strap provided with the eyelets or openings *a*, of the hook having the flat part 95 provided with the hooks or teeth to engage said openings, the neck having the seat for a link of the chain, and the detachably-connected bar provided with an arm forming a guard to prevent the escape of said link, substantially as specified.

In testimony whereof I affix my signature in presence of two witnesses.

ALFRED NEWTON CHANDLER.
